CHARLES F. PAPE, OF VANDERGRIFT, PENNSYLVANIA, ASSIGNOR TO HUTCHINS CAR ROOFING COMPANY, OF DETROIT, MICHIGAN, A CORPORATION OF MICHIGAN.

BUNG FOR METALLIC BARRELS.

1,170,182.

Specification of Letters Patent.

Patented Feb. 1, 1916.

Application filed July 30, 1914. Serial No. 853,999.

To all whom it may concern:

Be it known that I, CHARLES F. PAPE, a citizen of the United States of America, residing at Vandergrift, in the county of 5 Westmoreland and State of Pennsylvania, have invented certain new and useful Improvements in Bungs for Metallic Barrels, of which the following is a specification, reference being had therein to the accompanying drawings.

The invention relates to metallic barrels and has particular reference to the novel construction of bung and bushing therefor as hereinafter set forth.

15 In the drawings: Figure 1 is a central section showing the bushing as attached to a metallic barrel and the bung in engagement therewith; Fig. 2 is a similar view showing the bung removed and a hose connected to the bushing for filling the barrel; Fig. 3 is a similar view showing a tap secured to the bushing for withdrawing the contents from the barrel; and Figs. 4 and 5 are plan views respectively of the bushing and bung.

25 A is the wall of a metallic barrel; B is the bushing which may be formed of malleable casting, drop forging or other suitable material, and which is provided with a flange C for fitting against the inner face of the barrel wall and an outwardly projecting cylindrical portion D. The portion D is internally threaded to receive a corresponding threaded bung E, which is provided with a squared head F or other means for engaging 30 a wrench or tool therewith.

It is usually necessary to provide a gasket for a metallic bung to insure sealing against leakage of the liquid contents of the barrel. The necessity for this bushing I avoid by 40 providing the bushing B with an inwardly-extending flange G terminating in an outwardly-extending cone or tapering portion H. The bung E is recessed and has its walls I tapered correspondingly to the taper of the cone H. Thus when the bung is screwed 45 inward and is tightened against the cone H a liquid tight seal will be produced. For filling the barrel when the bung E is removed the threads of the portion D are adapted for engagement with a suitable 50 coupling at the end of the filling hose. Inasmuch, however, as the diameter of the bung is greater than the diameter of the tap 55 usually attached to the barrel, the flange G

and cone H are internally threaded as indicated at J, so as to be adapted to receive the shank of the tap K.

The construction as described is one which may be cheaply manufactured, and the bushing may be readily attached to the barrel body, either by soldering, electric welding, or by any other of the usual and well-known methods of attachment. The tapering seat for the bung dispenses with the necessity of a gasket, and the different diameters of the threaded portions provide for attachment with either large or small connections.

What I claim as my invention is:—

1. A barrel bushing comprising an outwardly extending internally threaded portion and an internally threaded portion of lesser diameter, and a bung externally threaded to engage said outwardly-extending portion, and adapted to exteriorly engage said internally threaded portion. 70

2. A barrel bushing, comprising an outwardly extending internally threaded portion, an inner portion having an internally threaded aperture of lesser diameter, an outwardly-extending conical seat surrounding said threaded aperture of lesser diameter, and a bung threaded for engagement with said outwardly-extending portion and recessed to form a conical bearing complementary to the conical seat upon said bushing member. 80

3. A barrel bushing, comprising a cylindrical member having an internally threaded portion at its outer end and a flange or head at its inner end having a concentric, internally threaded aperture of lesser diameter, a conical bearing formed upon said flange and projecting outward within the larger internally threaded portion, and a bung threaded for engagement with said larger internally threaded portion and having a recess with a conical wall for seating on said conical bearing. 90

4. A barrel bushing, comprising a cylindrical member having a head at one end projecting beyond the periphery of the cylinder to form a shoulder for seating against the barrel wall and extending inward, and increased in thickness with an internally threaded aperture in the thickened portion 100 concentric with said cylindrical portion, and a bung threaded for engagement with the larger internally threaded portion and bear- 105

ing against said portion of increased thickness, the contacting faces being correspondingly coned to form a liquid tight seal.

5. A barrel bushing, comprising two integral outwardly-extending annular portions, one within the other, the outer portion having an annular flange for internally engaging the barrel, and a bung having

threaded engagement with one of said portions and forming a lap joint with the other. 10

In testimony whereof I affix my signature in presence of two witnesses.

CHARLES F. PAPE.
